UNITED STATES PATENT OFFICE.

JAMES F. JARRELL, OF BILLINGS, MONTANA.

CALCULATOR.

1,068,390.

Specification of Letters Patent.

Patented July 22, 1913.

Application filed May 8, 1912. Serial No. 695,935.

To all whom it may concern:

Be it known that I, JAMES F. JARRELL, a citizen of the United States, residing at Billings, in the county of Yellowstone and State of Montana, have invented new and useful Improvements in Calculators, of which the following is a specification.

This invention relates to calculators, the object in view being to provide a simple and convenient device of the class described for quickly figuring out the cost and percentage of profit of any article of known weight, such as coal, wheat, oats, and the like, the device being also useful for computing the amount due to workmen in time offices, the device embodying, in connection with a suitable base and chart, an indicator, which, together with the chart, is graduated in such manner as to indicate the total cost, percentage of profit, etc., and having combined therewith means for adjusting the hand in connection with the supporting base, so that it may be frictionally retained at any given point to which it is adjusted.

With the above and other objects in view, the invention consists in the construction, combination and arrangement of parts, as will be hereinafter more fully described, illustrated in the accompanying drawings, and pointed out in the claim hereunto appended.

In the drawing: Figure 1 is a plan view of the calculator. Fig. 2 is a cross section through the same, taken in line with the indicator hand.

The calculator contemplated in this invention comprises essentially a base 1 which is quadrant shaped, as shown, comprising the two edges 2 and 3 arranged at right angles to each other, and the curved or arcuate edge 4, which is described from the point 5 as a center, at which point 5 the indicator hand 6 is pivoted. Along the outer curved edge 4 of the base, there is an upstanding flange 7 which extends inward, as shown at 8, to form an overhanging lip, beneath which the outer extremity of the indicator hand 6 moves in frictional contact. In order to provide for increasing or diminishing the frictional contact between the hand and the inwardly extending lip of the marginal flange, I provide adjacent to the pivot 5 a hand supporting quadrant or segment 9 which is wedge-shaped in cross section, upon which the indicator hand 6 bears. The pivot 5 has the upper end thereof threaded

to receive a thumb nut 10, so that by screwing the nut, 10, downwardly, the pivoted end of the hand is deflected sufficiently to elevate the outer extremity of the hand to a proportionate degree, thereby causing it to bear frictionally against the overhanging lip or flange 8, above referred to. By this means, the hand may be retained in a reliable manner at any point to which it has been adjusted. The hand is further provided with a knob 11 to facilitate swinging the hand around its pivotal center.

In connection with the base 1, I employ a chart, shown at 12, embodying radial rows 13 of figures, previously worked out and applied thereto, to indicate the results desired to be obtained. The hand 6 is provided with a central longitudinal slot 14, and at one or both sides of the slot 14, the indicator hand is graduated and figures are applied thereto complementary to the figures in the radial rows 13 on the chart, the rows of figures on the hand being complementary to and adapted to register with the figures in the radial rows of the chart. It is further designed to provide the chart with calendar spaces, as shown at 15, said spaces being shown as twelve in number to contain the twelve calendar months of the year.

It will be understood that interchangeable charts and indicator hands may be employed in accordance with the material upon which the calculations are to be made. For example, the chart illustrated in the accompanying drawings is especially designed with reference to sugar beets, as delivered by a farmer to a sugar factory, or receiving station. The outermost rows of figures along the curved edge of the chart represent the weight of dirty samples of beets, while the figures on the indicator hand give the weight of cleaned samples of beets, so that in moving the hand from left to right, the hand is stopped opposite the figure which represents the weight of the articles, as previously determined. For example, the hand is shown as moved to the number 30, so that the radial row of figures corresponding with the number 30 is shown through the observation slot 14 in the indicator hand.

Supposing now that the clean sample weighs twenty pounds, reference is made to the number 20 on the indicator hand, which shows the percentage in this case to be 33. In this way, the operator quickly arrives at the desired result, without the necessity of

separately figuring out each separate transaction, as the beets are received at the receiving station.

What is claimed is:

- 5 A calculator, comprising a quadrant shaped base, a movable indicator hand pivotally connected to the base at the point of the angle forming the center from which the arc of the quadrant is described, a chart 10 superimposed upon the base and having computing rows of figures radial to the center of movement of the indicator hand, said hand being provided with a longitudinal observation slot adapted to disclose a single radial 15 row of figures of the chart and being graduated and provided with figures complementary to those of the chart, a grooved rim

extending around the curved margin of the base in which the outer extremity of the indicator hand is guided and confined, and a 20 tension device at the pivot of the indicator hand for limiting the frictional engagement between the indicator hand and grooved rim, said tension device comprising a hand supporting segment of wedge - shape in cross 25 section, and a clamping screw forming the pivot of the hand.

In testimony whereof I affix my signature in presence of two witnesses.

JAMES F. JARRELL.
